UNITED STATES PATENT OFFICE.

SAMUEL T. WHITE, OF DAVENPORT, IOWA.

MECHANICAL MOVEMENT FOR WASHING-MACHINE WRINGERS.

1,088,859.

Specification of Letters Patent.

Patented Mar. 3, 1914.

Original application filed March 10, 1913, Serial No. 753,327. Divided and this application filed June 16, 1913. Serial No. 773,845.

To all whom it may concern:

Be it known that I, SAMUEL T. WHITE, a citizen of the United States, residing at Davenport, in the county of Scott and State of Iowa, have invented new and useful Improvements in Mechanical Movements for Washing-Machine Wringers, of which the following is a full, clear, and exact description.

10 My invention relates to laundry machines for domestic purposes, and particularly to mechanism for supporting and driving the wringer.

The principal object of my invention is 15 to provide means upon which the wringer is mounted, that can be moved longitudinally upon the supporting bench in a position next the tub of the washing machine to wring clothes directly into or from said 20 tub, or can be moved into any position between said tub and the farthest end of said bench for other purposes.

Another object of my invention is to 25 actuate the wringer by a master-shaft disposed longitudinally under the bench regardless of the position the wringer may be in.

Yet another object thereof is to provide 30 clutch mechanism that will enable the operator to impart the movement of the master-shaft to or disengage the same from the shaft actuating the wringer, whenever desired.

A further object of my invention is to 35 provide for a suitable elongation of the bench upon which the laundry apparatus is mounted so that it may accommodate other receptacles for the reception of the wash, whenever desired.

40 These and other objects I accomplish by the means hereinafter fully described, and as particularly pointed out in the claims.

In the drawings: Figure 1 is a side elevation of my invention. Fig. 2 is a transverse vertical section thereof taken on dotted line 2, 2, Fig. 1. Fig. 3 is a transverse vertical section taken on dotted line 3, 3, Fig. 1. Fig. 4 is a longitudinal vertical section taken on dotted line 4, 4, Fig. 2. 50 Fig. 5 is a transverse horizontal section taken just below the plane of the top of the bench.

Referring to the drawings, A represents 55 a bench, which is, preferably, of a width corresponding to the diameter of the wash-

ing machine tub B mounted upon one end thereof, and is of a length sufficient to accommodate and support two or more tubs arranged with the washing machine tub in tandem. This bench is supported by four legs, one at each corner, and at the end opposite the washing machine tub, it is provided with a slide or extension C, comprising two parallel wooden strips or reaches, which have their outer ends connected by a cross-bar, and are longitudinally adjustable in or out of slides secured to the underside of the top of said bench, substantially as shown. When this extension is drawn out, a basket or tub can be seated thereon, but it can be shoved back until the cross-bar C thereof comes in contact with the end of the bench, in which position it will be entirely out of the way.

The type of washing machine, which I prefer to use in conjunction with my improved mechanism, is fully illustrated and described in application for Letters Patent of the United States, filed by me February 8th, 1912, and numbered 676,178, and the means for actuating the dolly-shaft thereof are fully set forth and illustrated in an application for Letters Patent of the United States, filed by me March 10th, 1913, Serial No. 753,327, whereof this present application is a division.

The lower end of the dolly-shaft D passes up through the bottom of the tub and it has a suitable spur-wheel H secured to its lower end that is actuated by a horizontally disposed reciprocable rack h. The end of rack h opposite the spur-wheel is pivotally secured to the upper end of a link I, and the lower end of the latter is pivoted in a suitable bracket secured to the side-rail of the bench. This link is rocked back and forth by means of a connecting-rod K, one end of which latter is pivoted to the upper end of the link concentric with the center of the pivotal connection between the link and the rack and the other or opposite end of which is pivotally mounted on a suitable crankpin k projecting from a comparatively large gear L. Gear L is mounted on the adjacent end of a longitudinally disposed spindle m that is journaled in the bearing-boss n made integral with the vertical portion of a hanger M, and this gear L is driven by a small gear P mounted upon and revolvable with the longitudinally disposed master-

shaft N of the machine. This master-shaft is journaled in suitable bearings o, o secured to and depending from the end rails of the top of the bench midway between the sides 5 of the same, and is driven by a motor or otherwise, through the medium of a pulley on its extended end nearest the tub. This master-shaft is, between its bearings adjacent its actuating means and the clutch 10 for throwing the washing machine mechanism in or out of gear, made cylindrical, and the remainder of its length is, preferably, made square in cross-section. The drive-gear P is loosely mounted on the 15 master-shaft next the side of the hanger M, and is in mesh with the large gear L, and is slidable longitudinally on said shaft to a limited extent, but not enough to move out of engagement with gear L. The boss of 20 this gear P is engaged by the upturned end of a transverse rock-shaft R, journaled at one end in a hanger M, and at its opposite end in a suitable hanger s secured to and depending from the side rail of the bench, 25 and beyond this hanger s the said rock-shaft is bent vertically upward to form a handle. The opposite end of the boss of gear P is provided with a clutch member P' that is 30 adapted to engage an opposing clutch member x which is secured to and revolves with the master-shaft and is made in the adjacent end of a collar or coupling X, which latter enables me to make the master-shaft of two commercial forms of shafting, one 35 round and the other square in cross-section. Thus, it will be seen that when the rock-shaft R is rotated in the one direction, the clutch members will be thrown into engagement with each other and through the 40 junctive mechanism will actuate the dolly of the washing machine, and when the clutch mechanism is disengaged the dolly will no longer be actuated by said master-shaft.

Between the washing machine tub and the opposite end of the bench, angle-iron rails 2, 2, are secured in parallel relation so that their vertical portions overhang and are parallel to the longitudinal sides of the 50 bench. A traveling-frame, upon which the wringer mechanism is carried, is mounted and adjustable upon these rails. This frame consists of two corresponding standards or 55 uprights 3, 3, that are, preferably, made of wood, and have their lower ends inserted and secured in a rectangular depressed area of the center portion of the outer surface of T-shaped truck-frames 4, 4. The alining arms of these truck-frames are made with 60 inwardly projecting portions that overhang rails 2, and the inner extremities of said arms are, preferably, provided with two parallel vertical webs, between which the truck wheels 7 that run on rails 2 are journaled. The lower edge of the inner one of

these webs depends below that of the other and constitutes a guard that prevents said truck-frames from moving laterally off of the rails. Below the plane of the top of the bench the outer web of the ends of the alining arms of the truck-frames have inwardly projecting flanges 8 that extend toward and come under the overhanging portion of said rails and prevent said truck-frames from being accidentally lifted off the rails.

The lower ends or feet of the truck-frames are flat and of a flanged construction and are riveted or otherwise secured to a cross-bar 9 extending from one side of the machine to the other under the bench. At about its center of length this cross-bar 9, (which has portions cut out to lighten it) has a couple of bearings that are provided with flanged bushings 10^a having square bores through which the master-shaft extends, and between these bearings said master-shaft has a gear 10 mounted thereon the boss of which engages the flanges of said bushings and prevents longitudinal movement on said shaft. This gear 10 engages the circumferential teeth of a combined spur and bevel gear 12, which is secured upon a longitudinally reciprocal idle-shaft 14, whose ends are journaled in bearings 13, 13, depending down from the underside of the plate. At a suitable distance from the combination gear 12, I secure on this idle-shaft a bevel-gear 15, the face of which opposes the beveled teeth of the combination gear. Between these gears the lower portion of shaft 14 is seated in a U-shaped channel 16, which latter, at its center of length, has a downwardly projecting stud that is pivotally seated in a suitable socket or bearing in the adjacent end of a horizontally disposed transverse lever 18. This lever is fulcrumed at a suitable point on the opposite side of the master-shaft by means of a stud 19 projecting upwardly therefrom through bearings 20 in cross-bar 9 in which it is retained by means of a suitable cotter-pin or otherwise. The longer arm of this lever extends outwardly beyond the sides of the standard 3, and is engaged by the lower cranked end of a vertical rock-shaft 21. The lower end of 110 said rock-shaft is journaled in an end extension of the cross-plate, 9 and its upper end is journaled in a lug projecting outward from a plate 22 secured to the upper end of the standard by means of rivets that pass through the standards and through the vertical web of a flanged corner angle 23, which latter is employed to secure the wooden cross-bar 24 to the upper ends of the standards. Above plate 22, shaft 21 is provided with a suitable handle 25, and the boss of the latter prevents shaft 21 from falling down through the lug in which it is journaled. By moving handle 25 in one direction, lever 18 will be moved so that it 115 120 125 130

will shift shaft 14 longitudinally in one direction, and when the handle 25 is moved in the opposite direction, shaft 14 will be moved longitudinally in the reverse direction. When the lever 18 is maintained in a position at right angles to the master-shaft, combination gear 12 and bevel gear 15 will run free, but when idle-shaft 14, upon which they are mounted, is moved longitudinally, the bevel teeth of the combination gear 12 will engage the adjacent side of an intermediate bevel gear 26, and drive the transverse shaft 27, upon the adjacent end of which it is secured, in one direction, or the bevel gear 15 will engage the opposite side of gear 26 and drive the shaft 27 in the opposite direction.

Shaft 27 is journaled in suitable bearing bosses depending down from cross-plate 9, and extends out beyond the outer surface of standard 3 on the same side of the machine, where it is provided with a sprocket-wheel 28. This sprocket-wheel is connected by a suitable chain-belt 29 to a suitable sprocket-wheel 30, which latter is securely mounted upon the extended end of the shaft of one of the rollers of wringer 31.

I do not lay claim to any novelty of the construction of the wringer, which latter is securely mounted upon the cross-bar 24 connecting the upper ends of the standards.

In operation, it is usual to put the wash or work in the tub of the washing machine and thoroughly wash the same through the medium of the rotary reciprocable movement of the dolly. When the clothes are washed, the clutch is disengaged, and the cover of the tub is raised. Then lever 18 is rocked so as to impart the motion of the master-shaft to the transverse-shaft 27, and rotate the latter in the direction it is desired to revolve the rollers of the wringer, in the right direction, and then the clothes from the tub are fed between the rollers of the wringer and the water expressed therefrom and fed into the tub placed alongside of the washing machine tub. This second tub is usually supplied with clean water, and when the wash has been sufficiently rinsed, the traveling frame and wringer are moved longitudinally to the side of the rinsing tub diametrically opposite the washing machine tub, and from this second tub the clothes are put through the wringer into a tub of bluing water, and when the wash has all been conveyed to the tub of bluing water the traveling frame and wringer carried thereby are moved to the side of the tub of bluing water opposite the tub of rinsing water, on the end of the bench opposite the washing machine, and then the wash is put through the wringer into a basket or tub supported upon the sliding extension G. Of course, the method of using the wringer in relation to the washing from the washing machine

tub will, in all probability differ according to the custom of the operation, but it is apparent that the adjustability of the wringer to and from the washing machine tub will be of the utmost convenience, and the providing of a bench upon which this adjustment can take place, which will accommodate several tubs besides the tub of the washing machine, will greatly facilitate and expedite the laundry work.

What I claim as new is:

1. A mechanical movement for wringers comprising a suitable elongated support, a master-shaft having fixed bearings and extending longitudinally under said support, a traveling frame adjustable longitudinally on said support, a driving gear mounted on said shaft and movable with said frame, an idle-gear journaled on said frame and engaged by said driving gear, a transverse shaft journaled in bearings supported by said traveling frame adapted to be actuated through the medium of said idle-gear, and sprocket wheels and a chain connected to said idle-gear.

2. A mechanical movement for wringers comprising a suitable elongated support, a master-shaft having fixed bearings and extending longitudinally under said support, a traveling frame adjustable longitudinally on said support, a driving gear mounted on said shaft, a combined spur and beveled gear in mesh therewith, a longitudinally movable shaft upon which said combination gear is mounted, a beveled gear thereon facing the beveled teeth of the combination gear, a shaft, a pinion on one end thereof adapted to be engaged by either of said beveled gears, a driven-shaft, and means adapted to transmit the motion of said transverse shaft to said driven-shaft.

3. A mechanical movement for wringers comprising a suitable elongated support, a master-shaft having fixed bearings extending longitudinally below said support and made square in cross-section between its bearings, a driving frame longitudinally adjustable upon said support, a longitudinally movable shaft parallel to and deriving motion from said master-shaft, a pair of beveled gears on said longitudinally movable shaft, a lever fulcrumed mediate its ends one end of which is adapted to engage and move said last-mentioned shaft longitudinally, a vertical rock-shaft adapted to move said lever, a transverse shaft one end of which terminates adjacent the longitudinally movable shaft, a pinion carried on the adjacent end of said transverse shaft and adapted to engage one of said beveled gears, a horizontally disposed driven shaft, and means for transmitting the motion of said transverse shaft to said driven shaft.

4. A mechanical movement for wringers comprising a suitable support, a longitudi-

nally disposed master-shaft having fixed 5 bearings in said support, a traveling frame movable longitudinally on said support and comprising two upright standards, a cross-plate connecting the upper ends thereof, truck-frames to which said standards are secured, a driven shaft mounted on said traveling frame, and actuating means for said driven shaft carried by said frame and deriving motion from said master-shaft.

5. A mechanical movement for wringers comprising a suitable support, a longitudinally disposed master-shaft having fixed 10 bearings in said support, a traveling frame movable longitudinally on said support and comprising two upright standards, a cross-plate connecting the upper ends thereof, truck-frames to which said standards are secured, a driven shaft mounted on said traveling frame, a transmission shaft carried by said frame and arranged at an angle 15 to said master-shaft, means transmitting the motion of said master-shaft to said transmission-shaft, and separate actuating means connecting said transmission-shaft and driven shaft.

6. A mechanical movement for wringers comprising a suitable support, a longitudinally disposed master-shaft having fixed 20 bearings in said support, a traveling frame movable longitudinally on said support and comprising two upright standards, a cross-plate connecting the upper ends thereof, truck-frames to which said standards are secured, a driven shaft mounted on said traveling frame, a transmission shaft carried by said frame and arranged at an angle 25 to said master-shaft, gears transmitting the motion of said master-shaft to said transmission-shaft, and a chain and sprockets connecting said transmission-shaft and driven shaft.

7. A mechanical movement for wringers comprising a suitable support, a longitudinally disposed master-shaft having fixed 30 bearings in said support, a traveling frame movable longitudinally on said support and comprising two upright standards, a cross-plate connecting the upper ends thereof, truck-frames to which said standards are secured, a driven-shaft journaled on said cross-plate, a transmission-shaft carried by the lower portion of said frame, a pinion on 35 the end of said transmission-shaft nearest said master-shaft, a spur-gear splined on said master-shaft, an idle-pinion meshing with said spur-gear and adapted to transmit the motion of said master-shaft to said transmission-shaft, and actuating means 40 connecting said transmission-shaft and driven-shaft.

8. A mechanical movement for wringers comprising a suitable support, a longitudinally disposed master-shaft having fixed 45 bearings in said support, a traveling frame

movable longitudinally on said support and comprising two upright standards, a cross-plate connecting the upper ends thereof, truck-frames to which said standards are secured, a driven-shaft journaled on said cross-plate, a transmission-shaft carried by the lower portion of said frame, a pinion on the end of said transmission-shaft nearest 50 said master-shaft, a spur-gear splined on said master-shaft, two bodily shiftable beveled gears adapted to alternately engage 55 said pinion, and a spur-gear connected concentrically to one of said beveled gears, means for shifting said beveled gears, and actuating means connecting said transmission-shaft and driven-shaft.

9. A device of the kind specified comprising a suitable elongated support, parallel tracks to the top thereof, a traveling-frame comprising wheeled trucks movable on said tracks, standards secured to and arising from said trucks, a cross-plate connecting said standards, a driven-shaft journaled on said cross-plate, a master-shaft extending longitudinally under said support, and actuating means for said driven-shaft that are mounted on and movable with said traveling-frame and deriving motion from said master-shaft.

10. A device of the kind specified comprising a suitable elongated support, parallel tracks on the top thereof, a traveling-frame comprising wheeled trucks movable on said tracks, standards secured to and arising from said trucks, a cross-plate connecting said standards, a driven-shaft journaled on said cross-plate, a master-shaft extending longitudinally under said support, and gearing for said driven-shaft that is mounted on and movable with said traveling-frame and deriving motion from said master-shaft.

11. A mechanical movement for wringers comprising a suitable support, a longitudinal master-shaft having fixed bearings in said support, a traveling-frame longitudinally adjustable on said support, a driven-shaft carried by said frame above said support, actuating means for said driven-shaft comprising a longitudinally movable shaft parallel to and deriving motion from said master-shaft, a pair of beveled gears on said movable shaft, a lever fulcrumed mediate its ends, one end of which is adapted to engage and move said last-mentioned shaft longitudinally, a vertical rock-shaft adapted to move said lever, a transmission-shaft one end of which terminates adjacent the longitudinally movable shaft, a pinion carried on the adjacent end thereof and adapted to be engaged by one of said beveled gears, gearing connecting said movable shaft and master-shaft and means for transmitting the motion of said transmission shaft to said driven shaft.

12. A mechanical movement for wringers comprising a suitable support, a longitudinal master-shaft having fixed bearings on said support and made square in cross-section a portion of its length, a traveling frame longitudinally adjustable upon said support, a driven-shaft carried by said frame, means for actuating said driven-shaft comprising a traveling-gear mounted upon the square portion of said master-shaft, a combined spur and beveled gear in mesh therewith, a longitudinally movable shaft upon which said combination gear is mounted, a beveled gear upon the opposite end of said movable shaft, a lever fulcrumed mediate its ends one end of which is adapted to engage and move said last-mentioned shaft longitudinally, a transmission-shaft, a pinion on one end thereof adapted to be engaged by either of said beveled gears, and means adapted to transmit the motion of said transmission-shaft to said driven-shaft.

13. A mechanical movement for wringers comprising a suitable support, a longitudinal master-shaft having fixed bearings on said support and made square in cross-section a portion of its length, a traveling

frame longitudinally adjustable upon said support, a driven-shaft carried by said frame, a sprocket on the outer end of said driven-shaft, means for actuating said sprocket comprising a traveling gear mounted upon the square portion of said master-shaft, a combined spur and beveled gear in mesh therewith, a longitudinally movable shaft upon which said combination gear is mounted, a beveled gear upon the opposite end of said movable shaft, a lever fulcrumed mediate its ends one end of which is adapted to engage and move said last-mentioned shaft longitudinally, a transmission-shaft, a pinion on one end thereof adapted to be engaged by either of said beveled gears, a sprocket on the opposite end of said transmission-shaft, and a chain operatively connecting said last-mentioned sprocket with said first-mentioned sprocket and thereby transmitting the motion of said transmission shaft to said driven shaft.

In witness whereof I have hereunto set my hand this 11th day of June, 1913.

SAMUEL T. WHITE.
